UNITED STATES PATENT OFFICE.

ROBERT F. HALL, OF SCHENECTADY, NEW YORK.

TRUCK FOR RAILROAD ROLLING STOCK.

Application filed November 29, 1922. Serial No. 603,916.

To all whom it may concern:

Be it known that I, ROBERT F. HALL, a citizen of the United States, residing at Schenectady, in the county of Schenectady 5 and State of New York, have invented a certain new and useful Improvement in Trucks for Railroad Rolling Stock, of which improvement the following is a specification.

My invention relates to trucks for railroad rolling stock of the class or type in which lateral resistance devices are provided, and is an improvement on that set forth in Letters Patent of the United States No. 1,060,222, granted and issued to W. E.

15 Woodard, under date of April 29, 1918.

The object of my invention is to provide means whereby the resistance opposing the lateral movement of the truck bolster shall be caused to continuously decrease, coincidently with, and proportionately to, the increase of lateral movement of the bolster, thereby limiting the extent of vertical elevation of the bolster for a given lateral displacement, and exerting a relatively high 25 resistance during the initial movement of the bolster from its normal central position. A further object of my invention is to provide means for exerting a resistance which increases as the lateral displacement of the 30 bolster increases.

The improvement claimed is hereinafter fully set forth.

In the accompanying drawings: Figure 1 is a view, half in elevation and half in vertical central transverse section, of a two wheeled locomotive leading truck, embodying my invention; Figs. 2 and 3, similar sections through the truck frame and bolster, showing, respectively, the bolster moved 35 from normal central position through the distance a and through the distance b ; Fig. 4, a diagrammatic plan view, showing the disposition of the wheels of a 2-8-0 type locomotive on a curved track and the extent of lateral displacement of the bolster on such a curve; Figs. 5, 6 and 7, views, showing one of the rockers of Figs. 1, 2 and 3, with indications of the relation between the vertical and horizontal forces acting on the 40 bolster and rocker and their resultant, and, Figs. 8 and 9, similar views, showing the two positions of an increasing resistance rocker, with indications of the forces exerted in the two positions shown.

45 In "swing" or "lateral motion" type trucks

in which bolsters having inclined bottom bearings and cam shaped rockers are applied, the faces of the cam rockers are curved on radii, the centres of which are coincident with the axes of the segmental journals of the cams, about which the rockers swing when displaced from their normal middle positions. In the lateral movements of the bolster, the inclined bearings thereof move on the cam faces of the rockers, and the bolster is elevated, to an extent determined by that of the lateral displacement of the bolster and the inclination of its bearings. For example, if the bolster bearings are inclined one inch vertical rise for each 4 inches of projected horizontal length, the bolster will be raised one inch vertically for each 4 inches of lateral displacement, and other values of horizontal displacement will be accompanied by proportionate vertical elevations.

50 The extent of lateral displacement of the bolster varies directly with the wheel base proportions of the locomotive, and inversely with the radius of curvature of the track. It is also the practice, on some types of locomotives, to provide for additional lateral motion on the extreme pair or pairs of driving wheels, in which case the extent of lateral displacement on a curve of determined radius is increased. On locomotives having a comparatively long wheel base, it is desirable to provide a high lateral motion resistance in the leading truck, to assist in guiding the locomotive around curves, but the combination of a high lateral motion resistance, on a locomotive of this character, with a large extent of lateral displacement, involves liability to an undesirably great elevation of the bolster, tending to distort the spring rigging, etc. In order to reduce the extent of this elevation, the rockers are, in accordance with my invention, designed to give a relatively higher resistance, at the beginning of the lateral displacement, and a substantially lesser resistance at the full traverse of the bolster, the resistance decreasing uniformly from the initial to the final position. The extent of elevation of the bolster then becomes approximately the mean of the sum of the elevations which would be effected, with the same lateral displacement, by one bolster having an inclination of bearings giving the initial resistance, and another having an inclination corresponding to the final resistance, respectively.

It has also developed in practice, that locomotives equipped with a leading truck and no trailing truck, are subject to derailment when backing on curves, as in the case of those of the "consolidation" or 2-8-0 type, this condition being due to the fact that, in backing, the leading truck tends to crowd a rear driving wheel against the outer rail and to increase the flange pressure on that driving wheel. A reduction of the lateral resistance of the leading truck tends to lessen this objection, but if such reduction is made, the guiding effect of the truck in running forward is also reduced. In order to approximate the most favorable conditions, the resistance to lateral movement of the leading truck should be greatest on tangent track, so as to lessen the tendency of the locomotive to "nose"; should be less when running on the comparatively long radius curves on which the locomotive operates in continuous runs; and should be least, or entirely absent, when the locomotive is on curves of comparatively short radius, such as those on Y's and turnouts. With the leading truck resistance substantially eliminated, on the short radius curves last referred to, the flange pressure on the extreme driving wheels becomes practically the same for the going-ahead and the backing movements, and the flange pressure on an extreme driving wheel in backing is less than it would be if the leading truck exerted lateral resistance. The shorter the radius of the curve, with a given length of rigid wheel base, the sharper will be the angle that the flange of an extreme driving wheel makes with a tangent to the curve at that point, and the greater will be the tendency to derailment. It follows, consequently, that on the main line curves of relatively longer radius, a greater flange pressure may be exerted without tendency to derailment.

My invention is herein exemplified as applied in a two wheeled locomotive leading truck of the swing or lateral motion type, in which, as in present practice, a frame, 1, is supported through the intermediation of springs, 11, on the journal boxes, 4, of an axle, 5, on which the truck wheels, 5^a, are secured. A bolster support, 6, extends from one to the other of the side members of the truck frame to which it is rigidly secured at its ends. The weight carried by the truck is primarily applied thereto through a floating or swing bolster, 7, which is provided with a centre plate, 7^a, perforated for the passage of a centre pin. The bolster is supported, with the capacity of relative lateral movement, relatively to the truck frame, on the double curved upper bearing faces of two counterpart cam rockers, 9^a, upon each of which it abuts by double upwardly inclined or V shaped bearings, 7^b, formed on

its lower side. The cam rockers are adapted to swing, in one or the other direction, about the axes of segmental journals, 9^b, extending, parallel with the longitudinal centre line of the truck, on opposite sides of their bases, and fitting in correspondingly recessed bearings in the bolster support, 6.

In the practice of my invention, and as constituting its primary and essential characteristic feature, I provide, in a truck of the character hereinbefore described, cam rockers, 9^a, in which the bearing surfaces, 9^c, instead of being curved on radii, the centres of which are coincident with the axial lines of the journals on which the rockers swing, as in prior practice, are curved on radii, which are not coincident with said axial lines, that is to say, the centres of curvature are located either above or below the axes of swinging movement, thereby imparting a greater or a lesser degree of convexity to the bearing faces of the cam rockers, as the case may be. In the case of the location of the centres of curvature above the axes of swinging movement, the lateral resistance imparted to the bolster decreases continuously, as the lateral displacement of the bolster increases, and in the case of the location of the centres of the curvature below the axes of swinging movement, the lateral resistance imparted to the bolster increases continuously, as the lateral displacement of the bolster increases.

Figs. 5, 6 and 7, the cam rockers, 9^a, of which are similar to those of Figs. 1, 2 and 3, show the bearing surfaces, 9^c, of the rockers as curved on radii, the centres, x , of which are located above the axes of swinging movement, and, in Figs. 8 and 9, the bearing surfaces of the rockers are shown as curved on radii, the centres, y , of which are located below the axes of swinging movement. In the operation of rockers of the form shown in Figs. 5, 6 and 7, there is developed an increasing tendency of the bolster to slip on the surface of the rocker, the magnitude of which tendency is approximately measured by the tangent of the angle, z , which a line normal to the inclined surface of the bolster, makes with a line joining the axis of rotation of the rocker with the tangent contact point of the bolster on the rocker. For example, in a disposition giving 25 per cent initial resistance and zero resistance at full travel, if the inclination of the bolster bearings was made one in four (25 per cent) the angle, z , would be zero, in the initial central position, and the tangent of that angle in the final position would be equal to the bolster bearing inclination, i. e., 25 per cent, or, in other words, the tendency of the bolster to slide on the rocker in the final position would be measured by 25 per cent of the vertical load.

In order to reduce this slipping tendency at the end of the bolster movement by dis-

tributing it, I make the inclination of the bolster bearings less than the required initial resistance. For example, as shown in the drawings, the inclination of the bolster bearings is one in six (16 $\frac{2}{3}$ per cent). By suitably locating the centres of the bearing surfaces of the rockers, the positions of the tangent contact points of the bolster on the rockers are so shifted, relatively to the axes of swinging movement, as to afford an initial resistance of 25 per cent. Under this condition, there will be a slight tendency for the bolster to slip on the rockers, in its initial position, but this tendency, at the end of the traverse of the bolster, is reduced to approximately 16 $\frac{2}{3}$ per cent, instead of 25 per cent, of the vertical load.

It will, however, be obvious that any suitable and preferred inclination of the bolster bearings may be adopted, without departure from the spirit and operative principle of my invention.

I claim as my invention and desire to secure by Letters Patent:

- 23 1. In a railroad truck, the combination of a frame; a bolster adapted to traverse laterally relatively thereto; and a swinging rocker, journalled in bearings on the frame extending transversely to the bolster, said
- 20 rocker having cam surfaces abutting against the bolster, which cam surfaces are curved on radii, the centres of which are exterior to the axial lines of the rocker journals.
- 25 2. In a railroad truck, the combination of a frame; a bolster adapted to traverse laterally relatively thereto; and a swinging rocker, journalled in bearings on the frame extending transversely to the bolster, said
- 40 rocker having cam surfaces abutting against the bolster, which cam surfaces are curved on radii intersecting lines parallel with the

axial lines of the rocker journals and on centres located exterior to said axial lines.

3. In a railroad truck, the combination of a frame; a bolster adapted to traverse laterally relatively thereto, and having a plurality of double inclined or V-shaped bearings, the tangent of the angle of the inclined surface of said bearings with a horizontal line being less than the ratio of the maximum resistance to lateral displacement of the bolster; to the vertical load imposed on the rockers; and a swinging rocker, journalled in bearings on the frame extending transversely to the bolster, said rocker having oppositely curved cam surfaces abutting against the bearing of the bolster, and being curved on radii struck from centres inside the axial lines of the rocker journals on the side of the rocker opposite to that on which they are located.

4. A rocker for lateral motion railroad trucks, having oppositely curved cam surfaces adapted to abut against bearings on a bolster, and journals, transverse to its cam surface, on its lower ends, said cam surfaces being curved on radii the centres of which are exterior to the axial lines of the rocker journals.

5. A rocker for lateral motion railroad trucks, having oppositely curved cam surfaces adapted to abut against bearings on a bolster, and journals, transverse to its cam surface, on its lower side, said cam surfaces being curved on radii intersecting lines parallel with the axial lines of the rocker journals and on centres located exterior to said axial lines.
